[57] **CLAIM**

The ornamental design for a planter, as shown and described.

DESCRIPTION

FIG. 1 is a perspective view of a planter showing my new design;
FIG. 2 is a top plan view thereof;
FIG. 3 is a side elevational view thereof, all sides being identical;
FIG. 4 is a bottom plan view thereof;
FIG. 5 is a perspective view of a second embodiment of the design of FIG. 1, the only difference being an increase in diameter;
FIG. 6 is a top plan view of FIG. 5;
FIG. 7 is a side elevational view of FIG. 5, all sides being identical.

FIG. 1

FIG. 2

FIG. 4

FIG. 3

FIG. 5

FIG. 6

FIG. 7
